2 SHEETS—SHEET 2.

UNITED STATES PATENT OFFICE.

WALTER HEMPEL, OF PITCAIRN, PENNSYLVANIA.

ROTATABLE LANTERN.

1,177,102.

Specification of Letters Patent.

Patented Mar. 28, 1916.

Application filed March 13, 1915. Serial No. 14,115.

To all whom it may concern:

Be it known that I, WALTER HEMPEL, citizen of the United States, residing at Pitcairn, in the county of Allegheny and State of Pennsylvania, have invented certain new and useful Improvements in Rotatable Lanterns, of which the following is a specification.

This invention relates to improvements in car signals and more particularly to a device for reversing the signal lamp or lamps on locomotive tank cars, tenders and the like.

The object of the invention is to provide a simple and practical device of this character by means of which the fireman may readily reverse the lamps to have them show red for danger or green for safety from his usual position on the train and without the necessity of climbing up over the tender or tank.

Another object of the invention is to provide a device of this character which will not be rendered inoperative by reason of snow, ice, coal or other foreign matter coming in contact with it and which will set within the outside lines of the tank or car so as not to form an obstruction or interfere with the ordinary use of the car.

With the above and other objects in view, the invention consists of certain novel features of construction, and the combination and arrangement of parts as will be hereinafter more fully described and claimed.

In the accompanying drawings: Figure 1 is a rear end view with parts in section showing a portion of the tank car or tender having my invention applied; Fig. 2 is a detail sectional view taken on the plane indicated by line 2—2 of Fig. 1; Fig. 3 is a plan view of the oscillating lamp supporting base; Fig. 4 is a detail section taken on the line 4—4 of Fig. 2; Fig. 5 is a view of a pneumatic cylinder which may be connected to the lamp operating rod and used for actuating the same by means of compressed air, steam or the like; Fig. 6 is a bottom plan view of the lamp and the bracket; and, Fig. 7 is a detail sectional view taken on the line 7—7 of Fig. 2.

Referring more particularly to the drawings 1 denotes the tank car, tender or other car to which the invention is applied and 2 represents a substantially rectangular frame in which the signal lamp 3 is mounted. The box-like frame 2 is fastened by bolts 4 or

other suitable means at the opposite sides of the car 1 and they partially inclose the lamps to support and protect them.

In Fig. 1 of the drawings I have shown but one lamp on the left hand side but it is to be understood that a similar lamp is used on both sides and each has upper and lower cylindrical portions 5—6 which rotate freely within removable bearing loops 7—8 the ends of which are detachably secured by screws or similar fastenings 9 to opposite sides of the horizontal arms 10 of a U-shaped bracket 12. On the body portion or upright portion of the bracket 12 is formed a dove tail lug 13 adapted to fit in a similar shaped socket 14 formed in an attaching plate 15 secured by screws or other fastenings to the inner face of one wall of the casing 2 as clearly shown in Fig. 1. The bracket 15 has preferably formed on one of its sides a tubular socket 16 in which the staff of a signal flag 17 may be removably arranged.

The bearing bracket 12 steadies the lamp in its rotary or oscillatory movement and the lamp is supported by providing its base with a transversely extending lug 18 adapted to enter between angle metal plates 19 secured in spaced parallel relation on a rotatable supporting member or disk 20. The latter as shown in Fig. 1 has a radial flange 22 to which is secured a radially projecting arm 23 and on its base is formed a cup shaped portion 24 to receive a convex bearing member or block 25 arranged on the bottom of the frame or casing 2. The bearing block 25 and the disk 20 are formed with vertically aligned pivot openings to receive a pivot 26 preferably in the form of a bolt having its head countersunk in the top of the disk 20 and a nut 27 applied to its lower extremity below the bottom of the casing 2, see Fig. 1. It will be noted that the interlocking connection between the base of the lamp and the rotating member or disk 20 will cause the lamp to be turned when the arm 23 is actuated around the pivot 26.

The arm 23 is connected to a longitudinally extending operating rod 28 arranged along the side of the tender and said rod may be actuated manually or by compressed air, steam or other power. The rod 28 extends along one side of the tender or car and to protect it against snow, ice, coal and other foreign matter it is preferably arranged in a tubular casing or pipe 29 which

may be secured in place by eye bolts 30 or other fastenings and one end of which projects into one of the walls of the casing 2 as shown in Fig. 2. To permit of the manual 5 operation of the rod 28 a handle 31 is provided upon it within convenient reach of the fireman and at such point is also arranged a locking device consisting of a bearing block 32 to be bolted in place and having rectangular opening 33, see Fig. 4, to receive the rod 28, the latter being preferably similar shaped in cross section. Pivoted at 34 on one end 10 of the bearing 32 is a latch or dog 35 having a weighted end and handle 36 and two opposite projecting portions 37 either one of which may be swung into either one of two notches 38—39 formed in the rod 28, see Fig. 2. When either of said ends 37 is in the notch 38 the lamp will be locked in one position 15 and when the handle end 36 of the dog is elevated the rod 28 can be actuated until the other notch 39 is in operative position beneath the dog or latch whereupon one of its ends 37 may be dropped into said notch to 20 lock the lamp in its other position. It will be understood that the notches 38—39 are so positioned that the lamp will be given a quarter turn at each operation of the rod 28.

When the rod 28 is to be operated by 25 power the cylinder 40 is provided containing a piston 41 the rod 42 of which has a forked apertured end which may be connected to the apertured end of the rod 28 by a removable pin as will be readily understood. The 30 movement of the piston 41 is limited by stop screws 43 in the ends of the cylinder and at each end of said cylinder there is an inlet valve 44 and an outlet valve 45. The two inlet valves are connected by branch pipes 35 to a supply pipe 46 which leads from a suitable source of supply of compressed air, steam or other actuating fluid. Each inlet valve 44 is operatively connected by an operating rod 47 to the outlet valve 45 at 40 the opposite end of the cylinder so that when either inlet valve is opened by operating the operating rod 47 the outlet on the opposite

side of the piston is likewise opened as will be readily understood on reference to Fig. 5.

From the foregoing description taken in 50 connection with the accompanying drawings, the construction and operation of the invention will be readily understood without requiring a more extended explanation.

Various changes in the form, proportion 55 and the minor details of construction may be resorted to without departing from the principle or sacrificing any of the advantages of the claimed invention.

I claim as my invention:

The combination of a casing for attachment to a car having an opening in its bottom, a circular bearing block having a convex upper surface and a flat base to rest on said bottom, said block having a central pivot opening alining with the one in the casing bottom, a circular lamp supporting member having a flat top with a central pivot opening, the said member being provided with a cup-shaped bottom to rotate on said bearing block, a pivot bolt arranged in said pivot openings and having its head countersunk in said lamp supporting member, a radially projecting actuating arm on said lamp supporting member, a pair of spaced parallel angle metal strips secured on the flat top of said lamp supporting member on opposite sides of said pivot opening, an attaching plate secured on one of the upright walls of said casing, a U-shaped bracket having detachable engagement with said plate and provided with upper and lower bearing loops, a lamp having upper and lower cylindrical portions to rotate in said loops, and a rectangular rib centrally arranged on 70 the bottom of said lamp to enter between the upright flanges of said angle strips.

In testimony whereof I affix my signature in presence of two witnesses.

WALTER HEMPEL.
